UNITED STATES PATENT OFFICE

LAFAYETTE BEAN, OF FREDERICKSBURG, VIRGINIA, ASSIGNOR TO VIRGINIA SHOE COMPANY, INC., OF FREDERICKSBURG, VIRGINIA, A CORPORATION OF VIRGINIA

SHOE

Application filed December 5, 1927. Serial No. 237,875.

My invention consists in a new and useful improvement in shoes and is designed to produce a shoe in which is incorporated in the process of fabrication means whereby the inner sole provides adequate support for the arch of the foot of the wearer. The particularly novel and useful feature of my improvement resides in the configuration, proportion and disposition of the attachment 5 inserted between the inner sole and the middle sole of the shoe. This attachment, preferably made of leather, is so designed as to form both a wedge to raise a portion of the inner sole to provide an arch support, and 10 also an extension beyond the lines of the inner sole to afford additional support for the arch of the foot. I am aware that there are many forms of arch supports intended to secure the results contemplated for my improvement, but the novelty of my device, 15 over the others, consists in the peculiar form of the attachment, and its utility is greatly enhanced by its simplicity of manufacture and ease of application in the fabrication of 20 the shoe.

In the drawings filed herewith, I have illustrated and hereinafter fully described one specific embodiment of my invention but it is to be distinctly understood that I do not 25 consider my invention limited to said embodiment, but refer for its scope to the claim appended hereto.

In the drawings:

Fig. 1 is a longitudinal vertical section of 30 my improved shoe.

Fig. 2 is a transverse section on the line 2—2 of Fig. 1, viewed in the direction indicated by the arrow.

Fig. 3 is a top plan view of the inner sole 35 and its attachment.

Fig. 4 is a bottom plan view of the same.

Fig. 5 is a section on the line 5—5 of Fig. 3, viewed in the direction indicated by the arrow.

In the drawings:

The shoe has the upper U with lining L the lower edge of which is turned under the inner sole I to which is cemented the middle sole M with the outer sole O, the upper U having its edge stitched down with the welt W to the middle sole M and the outer sole O with stitches S, a lift F being provided to form the heel.

In my preferred form, I provide the inner sole I on its under side with an attachment A of novel form comprising two portions, viz., A—1 serving as a wedge interposed between the inner sole I and the middle sole M, and A—2 serving as an extension of the inner sole I retained in position by the lining L. As indicated in Figs. 3 and 4, this attachment A is applied at the inner edge of the shank of the inner sole I, and the inner edge of the portion A—1 forms a shoulder A—3 which is curved to conform with the curve of the shank at that point. The outer edge A—4 of A—1 is substantially semi-circular in form. The portion A—1 is so skived as to provide a curved surface A—5 between the edges A—3 and A—4 which merges with the inner sole I. This peculiar construction of the portion A—1 serves, when the attachment A is applied, to cause that part of the inner sole I above the portion A—1 to rise to serve as an arch support for the foot. Attention is called to the fact that the portion of the inner sole I above the portion A—1 is skived to render that part of the inner sole I more pliable. The extension portion A—2 is 50 notched at A—6 adjacent the shoulder A—3 of the portion A—1 in a curve corresponding with the curve of A—3, and is skived to a thin line at its inner edge A—7 so as to give the outer face of the portion A—2 a curved surface A—8.

Having described my invention, what I claim is:

A shoe having incorporated therein during its fabrication an inner sole having a 55

skived portion, and a wedge member inserted under said inner sole having a curved surface on its under side, a notch curved to conform to the curve of the inner edge of the shank of the inner sole and forming a shoulder thereunder, and its outer edge formed in substantially a semi-circular arc, and an extension integral with said wedge member having a curved inner edge conforming to the curve of the upper of the shoe against which it is positioned, and having a curved upper surface.

In testimony whereof I affix my signature.

LAFAYETTE BEAN.
